CLAIM

The ornamental design for a vacuum conduit pipe adapter as shown and described.

DESCRIPTION

FIG. 1 is a perspective view of a vacuum conduit pipe adapter showing the new design.

FIG. 2 is a front view thereof.

FIG. 3 is rear view thereof.

FIG. 4 is a right-side view thereof.

FIG. 5 is a left-side view thereof.

FIG. 6 is a top view thereof.

FIG. 7 is a bottom view thereof; and,

FIG. 8 is a sectional view thereof, taken along line 8-8 in FIG. 6.

In these drawings, the solid lines illustrate the claimed ornamental design, whereas broken lines, if present, illustrate unclaimed subject matter and form no part of the claimed design.

1 Claim, 8 Drawing Sheets
